UNITED STATES PATENT OFFICE

CHARLES W. HORTON, OF GRAND RAPIDS, MICHIGAN, ASSIGNOR, BY MESNE ASSIGNMENTS, TO JOHN E. STRONG, OF GRAND RAPIDS, MICHIGAN

FOLDING TABLE AND BENCH

Application filed September 26, 1927. Serial No. 221,941.

This invention relates to a folding table with seats combined therewith and is more particularly concerned with various improvements to be used in connection with the combined folding table and seats invented by John E. Strong having Patent No. 1,646,939, issued October 25, 1927.

It is an object and purpose of the present invention to provide a mounting for the folding table or the same with seats combined therewith so that the same may be received in a wall recess or pocket, or may be mounted upon the inner side of a door which closes a closet, provision being made for the elevation 10 of the inner support for the table and seats when the same are folded to collapsed position, thereby lifting the same above the usual bottom board at the lower end of such wall recess or closet, but automatically lowering 15 the same so as to rest upon the floor when in operative position. This insures a ready folding of the combined table and seats irrespective of rugs or other floor coverings which may be used and which, if provision was not 20 made for the automatic elevation described, would interfere with the folding of the structure into collapsed position.

A further object of the invention is to provide a simple means for effecting this automatic elevation and lowering with the folding and unfolding movements of the table and to associate therewith a counterbalance spring which will insure against accidental dropping of the table to its lower horizontal 35 position when it has been turned upwardly to folded and retracted position.

A still further object of the invention is to provide a construction whereby the table and the seats in conjunction therewith may be folded into a wall recess or closet so as to be entirely received therein, when in inoperative position yet in which the seats, when in use, are located entirely outside of said recess, use 40 being made of offset hinges in connecting the seat supports to the table supports for this purpose.

Various other objects and purposes will appear on understanding of the invention had 45 from the following description taken in con-

nnection with the accompanying drawings, in which,

Fig. 1 is a perspective view, partly broken away and shown in section, illustrating the combined table and seats in their outer operative position, the same being shown in conjunction with a wall receiving pocket therefor.

Fig. 2 is a similar perspective view of the table folded into said pocket and with one of 60 the seats folded against the underside of the table and within the recess, the other being in unfolded position.

Fig. 3 is a vertical section enlarged through the construction with the table in its folded 65 retracted position.

Fig. 4 is a similar section showing the table and seats in outer unfolded operative position.

Fig. 5 is a fragmentary enlarged vertical 70 section similar to that shown in Fig. 4, but illustrating the mechanism in greater detail.

Fig. 6 is a horizontal section through the construction shown in the position that it has in Fig. 2.

Fig. 7 is a section similar to that shown in Fig. 6 with the table and seats in outer operative horizontal position, and,

Fig. 8 is a fragmentary front elevation, the table and one of the seats being shown in 80 transverse vertical section illustrating the rear table support and the manner in which it is mounted for vertical adjustment.

Like reference characters refer to like parts in the different figures of the drawings. 85

The wall recess or pocket in which the table and seats are folded may be conveniently provided between vertical studding 1, which make the vertical sides of the pocket, there being a back 2, an upper end 3 and 90 a lower horizontal bottom board 4, which is located above the plane of the floor, the pocket or recess being surrounded by a border 5 so as to present a suitable appearance and one which may suggest a panel in the wall 95 of the room.

Within this pocket or recess, upper and lower bars 6 of flat metal are located parallel to each other and in horizontal planes, the ends 7 thereof being turned forwardly at 100

right angles so as to bear against the inner sides of the studding 1 to which they are permanently secured by means of screws. One of the bars 6, as shown in Fig. 3, is located a short distance above the bottom 4, while the other bar 6 is considerably higher. Each of the bars 6 are provided near each end with a forwardly extending headed pin 8. The upper bar 6 at its upper portion and on its front side is also formed with two forwardly extending lugs 9, one adjacent each end of the bar.

The rear support for the table comprises a frame of rectangular shape including upper and lower rails 10 and 11 respectively, connected at their ends by vertical sides 12. Two angle members 13 are secured to each of the rails 10 and 11 respectively. The upper angles 13 have horizontal legs passed underneath the upper rail 10 which extend upwardly and lie against the front face of the upper bar 6. The lower angle plates 13 have horizontal legs extending over the upper edge of the lower rail 11 and vertical legs which extend downwardly and lie against the front side of the lower bar 6. This is fully shown in Fig. 3. The horizontal legs of the angle members 13 are formed with vertical slots 14 through which the headed pins 8 pass. It is evident, therefore, that the inner or rear support for the table is mounted upon the bars 6 so that it may have limited vertical sliding movement within the limits prescribed by the slots 14 and the headed pins 8 passing therethrough.

The table 15, of a width to be received between the sides of the wall pocket or recess, is hinged adjacent its rear edge to the upper edge of the upper rail 10 of the rear support so that it may be turned to a vertical position, as shown in Figs. 1 and 2, or downward to a horizontal position as shown in Figs. 4 and 5. A leg 16 is hingedly connected at its upper end to the under side of the table toward the outer end of said table. From the inner end of the table 15 two lugs 17 extend lying in the same vertical plane with and directly above the lugs 9 previously described. When the table 15 is turned from the horizontal position, shown in Figs. 4 and 5, to the vertical position, shown in Figs. 2 and 3, the lugs 17 ride against the upper edges of the lugs 9 and cause a lifting of the inner supporting frame comprising parts 10, 11 and 12, so that it and anything connected therewith is lifted a limited distance, but when the table is turned downwardly to horizontal position, the lugs 17 also being turned to horizontal position, the table and this support therefor drop downwardly under the influence of their weight or until the lower end of said support either engages with the upper side of the board 4 or the rear seat supports (as are later described) engage against

the floor or rug thereon in front of the board 4, as shown in Fig. 5.

Two relatively heavy coiled springs 18 are connected at the upper ends, one to each lug 17, and at the lower ends to suitable hooks 19 secured to the backs of the sides 12 of the rear support. Said springs are stretched and tensioned when the table is dropped down to horizontal position and when the table is turned to vertical position act to maintain and hold the table in such position against accidental dropping down and also has some effect in rendering upward movement of the table easier.

The supporting legs 16 at its lower end has oppositely projecting feet 20. One leaf of a hinge 21 is rigidly secured to the outer end of each of said feet 20. Similarly one leaf of each of two hinges 21 is rigidly secured to the outer edge of each of the sides 12 of the inner or rear support for the table. A rear seat supporting member 22 is connected to the other leaves of the pair of hinges 21 attached to said sides 12. An outer seat supporting member 23 is connected at its lower end to the other leaf of each of the front hinges 21, as best shown in Fig. 1. The leaves of the hinges 21, which are connected to the feet 20, and to the sides 12, as described, are longer than the leaves which are connected to the seat supports 22 and 23. A seat 24 is hingedly connected to the upper end of each pair of seat supports 22 and 23, the seats being connected adjacent their inner ends to the seat supports 22 and adjacent their outer ends to the supports 23. As illustrated there are two of the seats 24, one on each side of the table, but it is evident that the invention is operative should one of the seats, its supports and their connecting hinges be removed.

As thus constructed, the table may occupy a horizontal position, as shown in Figs. 1, 4 and 5, the seats occupying a lower horizontal position at each side of the table. The inner seat supporting members 22 are turned outwardly from the inner table support and lie outside of the recess or wall pocket in front of the sides of the border 5. The lower ends of said supports 22 rest on the floor. This is possible by reason of the offset of the seat supporting members 22 from the support for the inner end of the table on account of the hinges used, permitting the inner table support to remain within the wall pocket or recess while the seat supporting members 22 are located outside thereof.

When the table with its seats is to be folded within the recess or pocket the table is gripped at its outer end and turned upwardly. As this occurs, as previously described, the lugs 17 ride upon the upper edges of the lugs 9, elevating the inner table support and, as the seat supporting members 22 are connected thereto, also elevating them so that the seat supporting members 22 are lifted from the

position shown in Fig. 5, where they rest upon the floor, to a position above the upper side of the board 4. By reason of the connection of the leg 16 with the outer seat supporting members 23 the seats are also turned to vertical position simultaneously with the movement of the table to vertical position, so that the seats and their supports at the end of the first movement of folding and retracting 10 the same are like as shown at the left in Fig. 2. Each seat 24 with its supports may then be turned inwardly to come against the under side of the table as shown at the right in Fig. 2, and by reason of the elevation of the 15 lower ends of the seat supporting members 22 above the board 4 of the wall pocket or recess the inward folding may be readily and easily accomplished. Also by reason of the difference in length of the hinge members making 20 up the hinges 21 the seats and supports may be readily inwardly folded, this being best illustrated at the upper end of Fig. 6.

While the invention has been illustrated in connection with a wall pocket or recess, it is 25 evident that it may be used for mounting the table and seats upon the rear side of a closet door. The mounting of the table upon the rear side of the door will be substantially identical with the mounting of the same in the 30 closet. That is, it will be mounted on the door to have a limited vertical movement whereby the inner support for the table and the inner or rear seat supports attached thereto are elevated when the table and seats 35 are folded against the door, thus providing the necessary elevation of the same above the usual bottom board for a wall recess or closet so that the door may be readily closed and also taking care of the possibility of rugs being 40 located on the floor over which the door and the table and seats attached thereto must swing when the door is opened. The invention is no different in its construction and the purposes which it has when mounted either 45 in a wall pocket or recess, as illustrated, or on the inner side of a closet door.

This invention is very practical and has proved especially useful in service. The wall recess or pocket in many respects simulates a 50 wall panel and the room presents a balanced and effective appearance when the table and seats are folded into the pocket substantially filling the same. The unfolding and lowering of the table and seats to lowered position 55 is very simple, requiring merely that the upper end of the table be grasped, drawn outwardly and turned to lower position after the seats have been turned outwardly.

The invention is defined in the appended 60 claims and is to be considered comprehensive of all forms of structure coming within their scope.

I claim:

1. In combination, a vertical support, a 65 table supporting member, means for mount-

ing said table supporting member on said vertical support for limited vertical movement, a table having hinged connection adjacent one end to said member for swinging movement about a horizontal axis, a leg 70 hinged to the under side of said table toward its other end, means projecting rearwardly from the hinged end of said table and means on said vertical support cooperating therewith when the table is swung from vertical 75 to horizontal position to permit lowering of said table supporting member and when the table is swung from horizontal to vertical position to elevate said supporting member.

2. In combination, a vertical support, a table supporting member, means for mounting said table supporting member on said vertical support for limited vertical movements, a table hinged at one end to said member for swinging movements from horizontal 80 to vertical position and vice versa, a leg hinged to the under side of the table for supporting the outer end thereof when the table is in horizontal position, lugs extending horizontally toward said vertical support from 85 the inner end of the table and cooperating lugs extending outward from said support for engagement by the first mentioned lugs, and acting to elevate the table supporting member when the table is swung from horizontal 90 to vertical position.

3. A construction containing the elements in combination defined in claim 2, combined with coiled springs attached at one end to 95 said lugs on the table and extending back of and attached to said table supporting member at their opposite ends, substantially as described.

4. In combination, a vertical support, two horizontal bars attached to said support one above the other, the uppermost of said bars having lugs projecting forwardly therefrom, a table supporting member located immediately in front of said bars, means for mounting said table supporting member on said bars for limited vertical movements, a table 100 hinged adjacent its inner end to said table supporting member to swing on a horizontal axis, lugs projecting from the inner end of the table and lying directly over the lugs on 105 said upper horizontal bar, whereby on movement of the table from horizontal to vertical position said lugs on the table bear against said lugs on the bar and automatically elevate the table supporting member a short distance, and means for supporting the outer 110 end of the table when it is turned to horizontal position.

5. A construction containing the elements in combination defined in claim 4, combined with coiled springs attached one to each of the lugs extending from the table, said springs 115 extending downwardly back of the table supporting member, and means connecting said 120

springs at their lower ends to said table supporting member.

6. In combination, a vertical support, two horizontal bars secured to said support, one spaced a distance above the other, headed pins extending forwardly from said bars, a table supporting member located immediately in front of the bars, angle plates attached to the table supporting member, each having a vertical leg with a vertical slot cut therethrough, said headed pins passing through said slots, a table hinged adjacent its inner end to the table supporting member to swing from vertical to a horizontal position and vice versa, and cooperating means at the inner end of said table and on the uppermost of said horizontal bars acting to automatically elevate the table supporting member when the table is swung from horizontal to vertical position.

20 In testimony whereof I affix my signature.

CHARLES W. HORTON.
